UNITED STATES PATENT OFFICE.

JAN BERGMANS AND THEODORUS JOSEPHUS JACOBUS ALPHONSUS MANDERS, OF EINDHOVEN, NETHERLANDS, ASSIGNOR TO GENERAL ELECTRIC COMPANY, A CORPORATION OF NEW YORK.

GAS-FILLED ELECTRIC INCANDESCENT LAMP.

Application filed November 4, 1927, Serial No. 231,130, and in the Netherlands December 21, 1926.

The invention relates to an electric incandescent gas filled lamp, such as a projection lamp with a highly concentrated filament and a filling of gas inert to the filament. The 5 filament in such lamps, which have an extremely high light intensity, is heated to very high temperature, with the result that evaporation occurs during which particles emitted from the filament deposit on the inside of the surrounding bulb. Owing to this 10 precipitation of these particles, the inside of the bulb becomes blackened or covered by a soot-like layer, which decreases the brightness of the lamp and causes the lamp to be 15 come unsuitable for purposes of illumination. Naturally, this blackening greatly diminishes the efficiency of the lamp and methods have been sought to prevent or diminish it.

One method which has been suggested is to 20 divide the lamp into sections in such a way that the differences in temperature in the different sections cause inside the lamp a flow of gases sufficient to conduct the particles thrown off by the filament into the comparatively 25 large bulb around the filament to some other part of the bulb where they do not have a detrimental influence on the radiation of light. However, this method requires that 30 separate partitions be constructed inside the lamp itself in order to divide it into sections.

The purpose of the present invention is to secure a forced draft inside the lamp without the use of partitions and without requiring that the lamp be divided into separate 35 sections. To this end the part of the bulb through which the light rays originating from the filament pass has been designed in such a way that it is tubular, surrounds the filament closely and is of comparatively small 40 bore. The concentrated filament is located at the end of the tubular part of the bulb, through which the leads for supplying current to the filament extend. In use the bulb is positioned in such a way that the filament 45 is located in the lower part of the bulb.

The gases, heated directly by the filament, will rise and will be conducted by means of the hot leads which carry the current to the filament to a part of the bulb where these 50 gases may cool off. After this cooling has occurred the comparatively cool gases move

downwards, following the inside of the tubular part of the bulb, and thus return to the filament. The cool gases moving downward act as though they surround the upward current of hot gases, and when reaching the lower part of the bulb the cool gases will move with some force along the inside of this part which surrounds the filament closely, as has been mentioned above. Due to the small 55 bore of the tubular part of the bulb immediately surrounding the filament no eddies or vortex motions occur in the currents of gases and, in addition, the desirable result is secured that the currents of gas are extremely 60 swift at this spot so that any black material which tends to deposit there will be scoured off and carried along by the current of gases 65 to another spot where the current is less swift.

In order to secure a good cooling effect at 70 a selected place the tubular part of the bulb may be expanded greatly to form a bulbous or spherical chamber in the neighborhood of the stem, while the filament is mounted in the end of the tubular part remote from this 75 chamber and as far as possible from the stem.

Two functions result from the expanding of the tubular bulb into a chamber, viz in the first place a cooling chamber is formed, and 80 in the second place a space is secured in which the fast moving gases lose their speed and permit precipitation of the particles thrown off by the filament. In order to increase the cooling artificial cooling may be applied to 85 the bulb in the neighborhood of the stem.

The construction also has the advantage that the filament is surrounded by a tubular glass envelope occupying very little space, while the expanded part of the bulb is located 90 at considerable distance from the filament. Owing to this feature the lamps are very suitable for use for projection purposes. This construction has certain advantages in optical systems using a lens or condenser, as well as 95 in those using a mirror. In the first place, the lens or condenser can be placed much closer to the light source, allowing a more compact construction, and in the second place the expanded part of the bulb is outside the cone of 100 light, so that the light rays are less deformed or weakened. It is, of course, understood that

the bulb must be manufactured of a kind of glass which can withstand the high temperatures which are present in the immediate proximity of the filament.

- 5 In the accompanying drawing which shows one embodiment of the invention, a concentrated filament 1 is mounted on the ends of a pair of straight parallel leads 2 and 3 which support the filament and also supply current 10 to it through the leading in wires 5 and 6 in the stem and the base 7 which is connected by a socket to a source of current. The filament and the leads are enclosed in a sealed gas filled bulb which contains an inert gas and has 15 a bulbous tubular part 8 of small bore closely surrounding the filament 1, and which is expanded into a spherical part or cooling chamber 9 in the neighborhood of the base 7.

When the lamp is lighted the filament 1 20 located near the sealed end of the tubular part 8 of the bulb will glow and consequently the surrounding inert gas will be heated. A similar heating of the gas takes place between the leads 2 and 3 which are preferably proportioned to be brought by the normal current flowing through them to a temperature high enough to heat the adjoining and surrounding gas sufficiently to cause it to flow upwards along the leads. If the lamp is 25 mounted base up so that the base 7 is above the filament 1, either in a slanting or in a vertical direction, then the heated gas will flow upwards along the leads with a velocity great enough to carry along the particles of 30 filament material and will flow into the spherical part or cooling chamber 9 which has a bore so much greater than that of the tubular part 8 that it loses velocity and deposits the particles of filament material. The 35 heated gas is cooled off at the surface of the spherical chamber, whereupon it flows downwards along the sides of the tubular part 8 until it reaches the lower end of the tubular part 8 of the bulb, where it will be again heated 40 by the filament. As the tubular part of the bulb which immediately surrounds the filament is of small bore, no eddies or vortex motions occur in the currents of gas, which attain a comparatively high velocity, thus 45 preventing the deposition on the bulb walls at this place of particles emitted by the filament. By means of this invention the glass of the lamp is kept clear for the entire life of the lamp exactly at those places through which 50 55 the light rays have to pass.

What we claim as new and desire to secure by Letters Patent of the United States, is:

1. A gas filled incandescent electric lamp comprising a pair of parallel leads proportioned to be heated by the normal current flowing through them to a temperature sufficient to cause a flow of the adjoining gas when the lamp is lighted, a concentrated filament on the end of said leads, and a sealed tubular bulb containing inert gas and enclos-

ing said leads and said filament with one end adjacent said filament and of a bore such that when the lamp is lighted currents of gas free from eddies flow along said leads and along said bulb walls with a velocity so great that 70 blackening of the bulb walls in the vicinity of the filament is substantially absent.

2. An incandescent electric lamp comprising a sealed bulb having a straight tubular portion closed at one end and expanded near 75 the other end into a bulbous chamber of considerably greater diameter than said tubular portion, a pair of straight parallel leads mounted in said tubular portion and extending from near its closed end into said chamber, and a concentrated filament mounted on the ends of said leads near the closed end of said tubular portion of the bulb, said tubular portion having a bore small enough to cause the currents set up in the gas in the bulb when 80 the lamp is lighted to flow with sufficient velocity to maintain the bulb walls adjacent said filament substantially free from blackening.

3. A gas filled incandescent electric lamp 85 comprising a sealed bulb containing an inert gas and having a straight tubular portion and a portion at one end enlarged to form a cooling chamber, a stem extending into said cooling chamber, a base on said cooling chamber 90 adjoining said stem, a pair of straight leads secured to said stem to extend through said cooling chamber and into said tubular portion and proportioned to be heated by the normal current flowing through them to a 100 temperature sufficient to cause the gas to flow along them, and a concentrated filament connected to said leads adjacent the other end of said bulb with a clearance between said filament and the walls of said tubular portion 105 so slight as to cause high velocity currents of gas free from eddies to flow along the walls of said tubular portion while the lamp is lighted.

4. An incandescent lamp comprising a 110 stem, a pair of straight parallel leads extending from said stem, a concentrated filament on the free ends of said leads, and a sealed bulb containing inert gas and enclosing said leads and filament, said bulb having a bulbous chamber adjacent said stem and surrounding said leads near said stem and a straight tubular portion extending from said chamber to enclose said leads and said filament with the opening into said chamber obstructed only by 115 said leads, said tubular portion having a bore small enough to cause currents in the gas free by said leads, said tubular portion having a bore 120 sufficiently great to permit the currents to decrease in velocity sufficiently to deposit in said chamber particles of filament material carried by the currents.

5. An incandescent electric lamp comprising 125

ing a sealed bulb having a straight tubular portion of small bore closed at one end and a spherical chamber of considerable greater diameter at the other end, a pair of straight leads extending through the opening of said tubular portion into said tubular portion, and a concentrated filament mounted on said

leads near the closed end of said tubular portion of the bulb.

In witness whereof, we have hereunto set 10
our hands this 8th day of October 1927.
